UNITED STATES PATENT OFFICE.

WILLIAM JOHN MERVYN, OF GULL LAKE, SASKATCHEWAN, CANADA.

GOPHER POISONER.

Application filed March 10, 1921. Serial No. 451,323.

To all whom it may concern:

Be it known that I, WILLIAM J. MERVYN, a citizen of the United States, and a resident of Gull Lake, in the Province of Saskatchewan and Dominion of Canada, have invented certain new and useful Improvements in Gopher Poisoners, of which the following is a specification.

This invention relates to improvements in dispensing devices and more particularly to a poison distributer for gophers.

An important object of this invention is to provide means whereby a predetermined quantity of poisoned grain or the like may be discharged from the distributer at will.

A further object of the invention is to provide a distributer of the class described which is simple, efficient and cheap to manufacture.

20 Other objects and advantages of the invention will be apparent during the course of the following description.

In the accompanying drawings, forming a part of this application and wherein like numerals are employed to designate like parts throughout the same,

Figure 1 is a side elevation of the improved distributer,

Figure 2 is a vertical transverse sectional view taken on line 2—2 of Figure 1,

Figure 3 is a fragmentary bottom plan view of the device.

In the drawing, wherein for the purpose of illustration is shown a preferred embodiment of the invention, the numeral 5 designates a body which as illustrated in Figure 1 is in the form of an annulus. The body or annulus 5 is supported by means of a pair of legs 6 having laterally projecting feet 7.

40 The upper portions of the legs are provided with attaching portions 7 secured to the annulus by means of rivets 8 or the like. A cylindrical receptacle 10 is arranged within the annulus 5 and is provided with an opening 11 adapted to be brought into registration with an opening 12 in the annulus 5 whereby wheat or the like may be introduced into the receptacle 10 from a hopper designated by the numeral 13. The cylinder 10

45 may of course rotate within the annulus 5 and is provided with a discharge opening 15 adapted to be brought into registration with an opening 16 in the bottom of the annulus.

55 When the openings 15 and 16 are in registration the poisoned wheat within the re-

ceptacle is discharged. However, the quantity of wheat to be discharged is not regulated by the degree of registration of the openings 15 and 16 but by a sliding door 60 17 supported beneath the opening 16 by a pair of guide flanges 18. One end portion of the sliding door 18 may be provided with a manipulating flange 20 by means of which the device may be manually gripped for adjusting the same. When the door is partially closed as illustrated in Figure 3, only a small quantity of grain may be discharged and when the door is entirely opened a larger quantity of grain may be discharged. The 70 cylinder 10 is provided at one end with a radial flange 21 which contacts with the adjacent end of the annulus for holding the receptacle against endwise movement in one direction.

75 The receptacle 10 is held against endwise movement in the other direction by means of an operating bar or handle 25 which is detachably secured to one closed end of the receptacle by means of screws or other 80 fastening devices 26. As illustrated in Figure 1, one end portion of the handle 25 extends above the receptacle while the other end extends below the same as indicated at 27 to cooperate with a pair of lugs 29 formed 85 on the legs to limit the rotary movement of the receptacle.

With reference to the foregoing description it will be apparent that a device constructed in accordance with this invention 90 may be employed for conveniently dispensing the desired quantity of grain for the purpose of poisoning gophers. The device is simple to operate, durable in use and may be manufactured at an extremely low cost. 95

Having thus described the invention, what I claim is:—

1. A poison distributer comprising an annular body, spaced legs supporting the annular body and having laterally projecting 100 lugs, a receptacle snugly and rotatably arranged in said body and having an annular flange engaging one side of the body whereby to limit the endwise movement of the receptacle in one direction, a handle connected 105 to said receptacle and having one terminal portion extending beyond the body and engaging said legs whereby to limit the rotation of the receptacle, and a hopper mounted on said body.

110 2. A poison distributer comprising a body, a cylindrical receptacle arranged within the

- body, said body and said receptacle being provided with discharge means, a door controlling said discharge means, and means to limit the rotation of said receptacle.
5. A poison distributer of the class described comprising an annulus, supporting legs secured to the annulus and having laterally projecting stop elements, a receptacle rotatably mounted within said annulus, said 50
10 annulus and said receptacle being provided with pairs of openings adapted for registration, a hopper secured to said annulus at the opening in said annulus, a door slidable over the other opening in said annulus, one 55
15 end portion of said receptacle being provided with a radial flange engaging the adjacent end of said annulus to limit the endwise movement of said receptacle in one direction, and a handle secured to the other 60
20 end of said receptacle and engaging the end of the annulus to limit the endwise movement of the receptacle in the other direction, one end of said handle being extended below the receptacle and cooperating with 65
25 said stop elements to limit the rotation of said receptacle.
4. A poison distributer comprising a body, a receptacle arranged therein, and a handle secured to one end of said receptacle and 70
30 contacting with the adjacent side of said body whereby to hold the receptacle against endwise movement in one direction, said receptacle being provided with an annular flange engaging the body to hold the receptacle against endwise movement in the other 75
35 direction.
5. A poison distributer comprising a body, a receptacle arranged therein and having an annular flange engaging one side of said body whereby to limit the endwise movement 80
40 of the receptacle in one direction, and a handle secured to one end of said receptacle and contacting with the adjacent side of said body whereby to hold the receptacle against 85
45 endwise movement in the other direction, said receptacle being provided with discharge means.
6. A poison distributer comprising a body, a receptacle arranged therein, a handle secured to one end of said receptacle and contacting with the adjacent side of said body whereby to hold the receptacle against endwise movement in one direction, and spaced stop elements associated with said body and arranged in the path of travel of said handle whereby to limit the rotation of said receptacle. 50
7. A poison distributer comprising a body, a receptacle arranged therein, a handle secured to one end of said receptacle and contacting with the adjacent side of said body whereby to hold the receptacle against endwise movement in one direction, and spaced stop elements associated with said body and arranged in the path of travel of said handle whereby to limit the rotation of said receptacle, said receptacle being provided with means engaging said body to hold the receptacle against endwise movement in the other direction. 60
8. A poison distributer comprising a body, a receptacle rotatable therein, said body and said receptacle being provided with discharge openings adapted for registration, a door carried by said body for controlling said openings, and a hopper for feeding said receptacle. 70
9. A poison distributer comprising a body having supporting means, a receptacle rotatably arranged therein, said body and said receptacle being provided with discharge openings adapted for registration, and a handle connected to said receptacle and engaging the body to hold the receptacle against endwise movement in one direction, one terminal portion of said handle being adapted to engage said supporting means whereby the rotation of the body is limited. 80
10. A poison distributer comprising a body, a receptacle arranged therein, said body and said receptacle being provided with discharge openings, legs connected to said body, and a handle connected to said receptacle and engaging said legs to limit the rotation of said body. 90

WILLIAM JOHN MERVYN.
